(57) **CLAIM**

The ornamental design for a hydraulic breaker vehicle tool and bracket assembly, as shown and described.

DESCRIPTION

FIG. 1 is an upper first side perspective view of a hydraulic breaker vehicle tool and bracket assembly;

FIG. 2 is a first side elevation view of a hydraulic breaker vehicle tool and bracket assembly;

FIG. 3 is a second side elevation view a hydraulic breaker vehicle bearing the subject tool and bracket, opposite said first side;

FIG. 4 is a front side elevation view of a hydraulic breaker vehicle tool and bracket assembly;

FIG. 5 is a rear side elevation view of a hydraulic breaker vehicle tool and bracket assembly, opposite said front side;

FIG. 6 is a top plan elevation view of a hydraulic breaker vehicle tool and bracket assembly;

FIG. 7 is a bottom plan elevation view of a hydraulic breaker vehicle tool and bracket assembly;

FIG. 8 is an upper first side perspective view of the hydraulic breaker vehicle tool and bracket assembly;

FIG. 9 is a first side elevation view of the hydraulic breaker vehicle tool and bracket assembly;

FIG. 10 is a second side elevation view of the hydraulic breaker vehicle tool and bracket assembly, opposite said first side;

FIG. 11 is a front side elevation view of the hydraulic breaker vehicle tool and bracket assembly;

FIG. 12 is a rear side elevation view of the hydraulic breaker vehicle tool and bracket assembly, opposite said front side;

FIG. 13 is a top plan elevation view of the hydraulic breaker vehicle tool and bracket assembly; and,

FIG. 14 is a bottom plan elevation view of the hydraulic breaker vehicle tool and bracket assembly.

The broken line showing of a hydraulic breaker vehicle tool and bracket assembly in FIGS. 1-7 is included for the purpose of illustrating environmental use only and forms no part of the claimed design.

1 Claim, 10 Drawing Sheets
